UNITED STATES PATENT OFFICE.

RICHARD T. CRANE, JR., OF CHICAGO, ILLINOIS.

ELECTRIC ILLUMINATED CLOCK-DIAL.

SPECIFICATION forming part of Letters Patent No. 618,646, dated January 31, 1899.

Application filed February 18, 1898. Serial No. 670,796. (No model.)

To all whom it may concern:

Be it known that I, RICHARD T. CRANE, Jr., a citizen of the United States, residing in Chicago, county of Cook, and State of Illinois, 5 have invented a certain new and Improved Illuminated Clock or Timepiece, of which the following is a specification.

Broadly stated, the object of my invention is to provide means for illuminating the index characters of a clock or timepiece, particularly such as are used in towers or upon the fronts of buildings, said means being arranged to illuminate each of the characters in turn and the whole being provided with 15 suitable devices actuated by the mechanism of the timepiece to control the illuminating means.

More specifically, the object of my invention is the provision of a clock provided with 20 suitable means for illuminating the index characters of the same, such illuminating means being arranged so that they will be controlled by the mechanism of the clock and so that as the hour-hand passes before each 25 of the index characters upon the dial such index characters will be illuminated, while at the same time all of the other index characters upon the dial are not illuminated.

In the practice of my invention I employ, 30 preferably, a dial provided with a diaphanous portion having index characters thereon, and back of each index character I arrange an electric lamp combined with suitable circuit-closing devices, whereby said lamp is illuminated during the period when the hour-hand 35 is traveling past it. As a means for regulating or controlling the lighting of the different lamps in turn I provide an arrangement of contacts preferably near the center of the dial 40 and acted upon by a brush or brushes carried around by the hour-hand.

A further object of my invention is the provision of an illuminated minute-hand combined with suitable means for keeping the 45 same in circuit with a source of electricity.

The above, as well as such other objects as may hereinafter appear, I have illustrated in preferred form in the accompanying drawings, in which--

50 Figure 1 is a front view of my illuminated clock. Fig. 2 is a side view of the same, partly

in section. Fig. 3 is a diagrammatic representation showing the wiring and arrangement of the lamps; and Fig. 4 represents a modified form of dial which may be used, if 55 preferred.

Referring now more particularly to Figs. 1 and 2, it will be seen that I have shown a clock-dial 5, having the index characters arranged upon a diaphanous portion thereof 6. 60 Back of each index character I arrange an electric lamp 7, each connected in circuit between a conductor-ring 8 and a segmental contact-piece 9, near the center of the dial. Inside of the circle of segmental contact-pieces 65 9 I arrange a contact-ring 10, which is connected by a wire to a dynamo or other suitable source of electricity, the other terminal of such source of electricity being connected to the ring 8. 70

Upon the hour-hand 11 I arrange a brush or brushes 12, constructed to travel around in contact with the ring 10 and the segmental contact-pieces 9, for the purpose of completing the circuit between the ring and each of 75 the contact-pieces in turn. By this arrangement, as is clearly obvious, the contact-piece, which is connected with the lamp behind the index character over which the hour-hand is passing, will be in circuit with the source of 80 electricity and kept lighted during the whole period of time that the hour-hand is moving past; but as soon as the hour-hand passes a point midway between two index characters the brush 12 snaps over or down upon the 85 next segmental contact-piece 9 and throws the next lamp into circuit.

Upon the outer end of the minute-hand 13 I arrange a lamp 14, connected by the wires 15, the brush 16, the wire 17, and the wire 18 90 (which is attached to one of the bearings of the minute-hand spindle) to the source of electricity, the contact being continuous, so that the light upon the minute-hand will burn constantly and thus indicate clearly at all 95 times the position in front of the dial.

It is obvious that with clocks embodying my invention it will be much easier to tell the time at night and at a distance than it would be with clocks of ordinary construction. 100

While in Fig. 1 I have shown a dial of ordinary form, this detail as well as others

might of course be modified in many regards without departing materially from the spirit of my invention. For example, in Fig. 4 I have illustrated a dial in which the ordinary index characters are arranged within a transparent ring, upon which the ordinary numerals may be placed, as shown.

If desired, each index character could be formed of a group of lights arranged in a manner similar to that used in forming the letters of illuminated signs. This arrangement could be conveniently used in applying my invention to clocks already in use.

In Fig. 3 I have illustrated, diagrammatically the location or arrangement of the different lamps and the circuit connections thereto, which have been already fully described. This figure also shows a source of electricity.

Having thus described my invention, what

I claim as new, and desire to secure by Letters Patent, is—

1. The combination with a clock-dial and an indicating-pointer moving over the same, of means for illuminating the indicating characters successively and synchronously with the registration therewith of the pointer.

2. The combination with a clock-dial and an indicating-pointer moving over the same, of means for illuminating the indicating characters successively and synchronously with the registration therewith of the pointer, said means being controlled by mechanism of the clock.

RICHARD T. CRANE, JR.
